CONTAINER

Charles F. McAleer, Kalamazoo, Mich., assignor
to Sutherland Paper Company, Kalamazoo,
Mich.

Application January 3, 1933. Serial No. 649,823

16 Claims. (Cl. 229—52)

The main objects of this invention are:

First, to provide a container for various products such as food products, for example lard or other relatively heavy materials, which provides an attractive package for the material and also is well adapted for handling by the purchaser or delivering the product to the purchaser.

Second, to provide a container formed of box or container board and having a handle which is strong and convenient to grasp.

Third, to provide a container having these advantages which is very economical to produce and may be formed of a blank adapted to be shipped in the knock-down and readily set up by the packer.

Objects relating to details and economies of my invention will appear from the description to follow. The invention is defined and pointed out in the claims.

20 A structure which is a preferred embodiment of my invention is illustrated in the accompanying drawings, in which:

Fig. 1 is a perspective view of a container embodying the features of my invention.

25 Fig. 2 is a perspective view of the container adjusted for carrying.

Fig. 3 is a transverse section on line 3—3 of Fig. 1.

30 Fig. 4 is a transverse section on line 4—4 of Fig. 2.

Fig. 5 is an enlarged detail section on line 5—5 of Fig. 1 showing details of the cover-secur-

ing means.

35 Fig. 6 is an enlarged detail section on a line corresponding to line 6—6 of Fig. 2 showing details of the securing means when the container is adjusted for carrying.

40 Fig. 7 is an enlarged fragmentary plan view showing the relation of the grip members of the inner and outer cover flaps.

Fig. 8 is a plan view of the blank from which the container illustrated in Figs. 1 to 6 is formed.

Fig. 9 is a perspective view of a modified form or embodiment of my invention.

45 Fig. 10 is a fragmentary longitudinal section on line 10—10 of Fig. 9.

Fig. 11 is a transverse section on line 11—11 of Fig. 9.

Fig. 12 is a plan view of the blank from which 50 the embodiment shown in Figs. 9, 10 and 11 is formed.

In the embodiment of my invention illustrated in Figs. 1 to 8 inclusive, the container is formed of an integral blank, shown in Fig. 8, and comprises a bottom 1, sides 2 and 3 disposed in align-

ment. The side wall 3 has a cover flap or extension 4 while the side wall 2 has a cover flap or extension 5.

The bottom 1 is provided with end wall flaps 6, 6 while the side wall 2 has end wall flaps 7, 7. 60 The side wall 3 has end wall flaps 8, 8. The end wall flaps 8, 8 are provided with locking tongues 9 engageable with slits 10 in the end wall flaps 7, thereby locking the end walls together and the container in erected position. The end wall flaps 65 8 have cover flaps 11 on their upper edges adapted to be folded within the cover flaps 4 and 5.

The blank is formed of box board or container board and is suitably scored as indicated by dotted lines to facilitate folding on predetermined 70 lines.

The cover flap 4 is, in the embodiment illustrated, relatively narrow and is provided with a tongue-like grip 12 transversely slit at 13 and longitudinally scored at 14 so that portions of its 75 edges may be folded or turned upwardly into flanges 15.

The outer cover flap 5 has a hand hole opening 16 therein with a central cross bar-like grip portion 17. This grip portion is transversely slit at 18 and longitudinally scored at 19 to provide flanges corresponding to the flanges 15 of the inner grip, the grip 17 being disposed so that it overlies the grip 12 and the flanges of the grips 80 20 may be turned upwardly into overlapping relation, as shown in Figs. 1 and 2.

The outer cover flap 5 has longitudinal scores 20, 21, 22 and 23. These scores facilitate the bending of the outer cover member and its adjustment to an arched carrying position as shown in 90 Fig. 2. The score lines 23 also provide a securing flap 24 which has tongues 25 at its ends engageable with vertical slits 26 in the side wall 3, the score line 22 permitting the lapping of the flap upon the side wall 3 and engagement with the slits 26 below the breaks 27 therein, as is shown in Fig. 1. These portions 27 are easily fractured so that an upward pull on the outer cover flap which may be done by grasping the grip will break or fracture these parts 27 allowing 100 the tongues 25 to slide longitudinally in the slits to the position shown in Fig. 2. The same upward pull, owing to the scoring of the outer cover flap referred to, allows it to assume the position shown in Fig. 2 and brings the grip portions and their flanges into overlapping relation.

The flanges on the inner grip underlie the flanged edges of the outer grip so that the hand, in grasping the grip, holds these parts in clamping engagement, with a result that a substan- 110

tial part of the load is sustained by the inner cover flap, and there is, in effect, an interlocking of the ends of the flanges of the inner grip member with the edges of the hand opening in the 5 outer cover flap.

The modified form or embodiment of my invention shown in Figs. 9 to 12 inclusive is formed of a blank shown in Fig. 12 which comprises a bottom 30, sides 31 and 32, inner top flap 33 on 10 the side 32, and outer top flap 34 on the side 31. The bottom is provided with end flaps 35 while the side walls 31 and 32 have overlapping interlocking flaps 36 and 37. The end flaps 36 have inner cover flaps 38. The side wall cover flap 15 33 has a grip 39 corresponding to the grip 12 while the outer cover flap 34 has a relatively narrow tongued flap 40 engageable with a longitudinal slit 41 in the side wall 2, the tongue overlapping and being secured to the side wall. 20 In this structure, the outer cover flap 34 is not adjustable to an arched position but the handle may be grasped by slightly depressing the end wall flaps, as is illustrated in Fig. 10. The securing flap 40 is preferably centrally scored to facilitate 25 engagement with the slit 41.

I have illustrated and described my improvements in two embodiments which I consider very practical. I have not attempted to illustrate and describe other embodiments or adaptations as it is 30 believed that this disclosure will enable those skilled in the art to embody or adapt my improvements as may be desired.

Having thus described my invention, what I claim as new and desire to secure by Letters 35 Patent, is:

1. A container formed of an integral blank and comprising aligned bottom and side walls, the bottom having end wall flaps on its ends and the side walls having overlapping end wall flaps on 40 their ends provided with interlocking portions, the outer of said interlocking end wall flaps having inner cover flap extensions on their upper edges, said side walls having overlapping inner and outer cover flaps, the inner cover flap having 45 a central tongue-like grip slit transversely and scored adjacent its edges to provide flanges on its longitudinal edges, the outer cover flap having a hand opening therein with a central grip overlying the grip of said inner cover flap and transversely slit and scored adjacent its edges to provide flanges overlapping the flanges on the inner 50 grip member, the said outer cover flap being longitudinally scored to provide a securing flap which overlaps the side of the container and to facilitate bending at the ends of the grip, said securing flap 55 having tongues and the side wall overlapped by said securing flap having vertical slits with which said tongues are engageable, the slits being of such length as to permit movement of the tongues longitudinally thereof and having intermediate 60 fracturable portions normally retaining the outer cover flap in collapsed closed position but permitting its elevation to carrying position without disengagement of the tongues from the slits.

2. A container formed of an integral blank and comprising aligned bottom and side walls, the bottom having end wall flaps on its ends and the side walls having overlapping end wall flaps on 65 their ends provided with interlocking portions, the outer of said interlocking end wall flaps having inner cover flap extensions on their upper edges, said side walls having overlapping inner and outer cover flaps, the inner cover flap having 70 a central tongue-like grip slit transversely and

scored adjacent its edges to provide flanges on its longitudinal edges, the outer cover flap having a hand opening therein with a central grip overlying the grip of said inner cover flap and transversely slit and scored adjacent its edges to provide flanges overlapping the flanges on the inner grip member, the said outer cover flap being longitudinally scored to provide a securing flap which overlaps the side of the container and to facilitate bending at the ends of the grip, said securing flap having tongues and the side wall overlapped by said securing flap having vertical slits with which said tongues are engageable.

3. A container formed of an integral blank and comprising aligned bottom and side walls, said side walls having overlapping inner and outer cover flaps, the inner cover flap having a central tongue-like grip slit transversely and scored adjacent its edges to provide flanges on its longitudinal edges, the outer cover flap having a hand opening therein with a central grip overlying the grip of said inner cover flap and transversely slit and scored adjacent its edges to provide flanges overlapping the flanges on the inner grip member, the said outer cover flap being longitudinally scored to provide a securing flap which overlaps the side of the container and to facilitate bending at the ends of the grip, said securing flap having tongues and the side wall overlapped by said securing flap having vertical slits with which said tongues are engageable, the slits being of such length as to permit movement of the tongues longitudinally thereof and having intermediate fracturable portions normally retaining the outer cover flap in collapsed closed position but permitting its elevation to carrying position without disengagement of the tongues from the slits.

4. A container formed of an integral blank and comprising aligned bottom and side walls, said side walls having overlapping inner and outer cover flaps, the inner cover flap having a central tongue-like grip slit transversely and scored adjacent its edges to provide flanges on its longitudinal edges, the outer cover flap having a hand opening therein with a central grip overlying the grip of said inner cover flap and transversely slit and scored adjacent its edges to provide flanges overlapping the flanges on the inner grip member, the said outer cover flap being longitudinally scored to provide a securing flap which overlaps the side of the container and to facilitate bending at the ends of the grip, said securing flap having tongues and the side wall overlapped by said securing flap having vertical slits with which said tongues are engageable.

5. A container formed of an integral blank and comprising aligned bottom and side walls, the bottom having end wall flaps on its ends and the side walls having overlapping end wall flaps on their ends provided with interlocking portions, the outer of said interlocking end wall flaps having inner cover flap extensions on their upper edges, said side walls having overlapping inner and outer cover flaps, the inner cover flap having a grip, the outer cover flap having a hand opening therein with a grip overlying the grip of said inner cover flap, the said outer cover flap having a tongued securing means which overlaps the side of the container, the side wall overlapped by said securing flap having slits with which said tongues are engageable, the slits being of such length as to permit movement of the tongues longitudinally thereof but permitting the elevation of said cover to carrying position without disengagement of the tongues from the slits.

6. A container formed of an integral blank and comprising aligned bottom and side walls, the bottom having end wall flaps on its ends and the side walls having overlapping end wall flaps 5 on their ends provided with interlocking portions, the outer of said interlocking end wall flaps having inner cover flap extensions on their upper edges, said side walls having overlapping inner and outer cover flaps, the inner cover flap having 10 a grip, the outer cover flap having a hand opening therein with a grip overlying the grip of said inner cover flap, the said outer cover flap having a tongued securing means which overlaps the side of the container, the side wall overlapped by 15 said securing flap having slits with which said tongues are engageable. 80
7. A container formed of an integral blank and comprising side walls having overlapping inner and outer cover flaps, the inner cover flap having 20 a grip, the outer cover flap having a hand opening therein with a grip overlying the grip of said inner cover flap, the said outer cover flap having a tongued securing means which overlaps the side of the container, the side wall overlapped by 25 said securing flap having slits with which said tongues are engageable, the slits being of such length as to permit movement of the tongues longitudinally thereof but permitting the elevation of said cover to carrying position without disengagement of the tongues from 30 the slits. 85
8. A container formed of an integral blank and comprising aligned bottom and side walls having overlapping inner and outer cover flaps, the inner cover flap having a grip, the outer cover flap having a hand opening therein with a grip overlying the grip of said inner cover flap, the said outer cover flap having a tongued securing means which overlaps the side of the 35 container, the side wall overlapped by said securing flap having slits with which said tongues are engageable. 90
9. A container comprising side walls having overlapping inner and outer cover flaps, the inner cover flap having a grip slit transversely and 40 scored adjacent its edges to provide flanges on its longitudinal edges, the outer cover flap having a hand opening therein with a grip overlying the grip of said inner cover flap and transversely 45 slit and scored adjacent its edges to provide flanges overlapping the flanges on the inner grip member, the said outer cover flap being longitudinally scored to provide a securing flap which 50 overlaps the side of the container and to facilitate bending at the ends of the grip, said securing flap having tongues and the side wall overlapped by said securing flap having slits with which said tongues are engageable, the slits being of such length as to permit movement of the tongues longitudinally thereof and having 55 intermediate fracturable portions normally retaining the outer cover flap in collapsed closed position but permitting adjustment of said cover to carrying position without disengagement of the tongues from the slits. 100
10. A container comprising side walls having 60
- overlapping inner and outer cover flaps, the inner cover flap having a grip, the outer cover flap having a hand opening therein with a grip overlying the grip of said inner cover flap, the said outer cover flap being longitudinally scored to provide a securing flap which overlaps the side of the container and to facilitate bending at the ends of the grip, said securing flap having tongues and the side wall overlapped by said securing flap having slits with which said tongues are engageable. 85
11. A container comprising opposed walls having inner and outer cover flaps, the inner flap having a grip provided with flanged longitudinal edges, the outer cover flap having a hand opening therein with a grip overlying the grip of said inner cover flap, the flanges of said inner grip embracing the outer grip when in carrying position, the outer cover flap having adjustable securing means whereby the outer cover flap may be collapsed to closed position or adjusted to an elevated carrying position. 90
12. A container comprising opposed walls having inner and outer cover flaps, the inner flap having a grip provided with flanged longitudinal edges, the outer cover flap having a hand opening therein with a grip overlying the grip of said inner cover flap, the flanges of said inner grip embracing the outer grip when in carrying position, the outer cover flap having securing means. 95
13. A container comprising opposed walls having inner and outer cover flaps, the inner flap having a grip, the outer cover flap having a hand opening therein with a grip overlying the grip of said inner cover flap, the outer cover flap having adjustable securing means whereby the outer cover flap may be collapsed to closed position or adjusted to an elevated carrying position. 100
14. A container comprising opposed walls having inner and outer cover flaps provided with superimposed grip members, the outer cover flap having a hand opening, the grip members extending across the hand opening and having outwardly directed superimposed flanges, the flanges of the inner grip member being disposed through the opening in the outer cover flap and with their ends in engagement with the edges of the opening. 110
15. A container comprising opposed walls having overlapping cover flaps provided with superimposed grip members, the outer cover flap having a hand opening, the grip members extending across the hand opening, the inner grip member having outwardly directed flanges disposed through the opening in the outer cover flap and with their ends in engagement with the edges of the opening. 115
16. A container comprising opposed walls having overlapping cover flaps provided with superimposed grip members, the outer cover flap having a hand opening, the grip members extending across the hand opening, the inner grip member having outwardly directed flanges disposed through the opening in the outer cover flap. 120

CHARLES F. McALEER.
